UNITED STATES PATENT OFFICE.

ABRAHAM A. SCHIMMEL, OF BOSTON, MASSACHUSETTS.

HAMMOCK.

1,090,108.

Specification of Letters Patent. Patented Mar. 10, 1914.

Application filed December 30, 1912. Serial No. 739,272.

To all whom it may concern:

Be it known that I, ABRAHAM A. SCHIMMEL, a citizen of the United States, residing at Boston, in the county of Suffolk and State of Massachusetts, have invented certain new and useful Improvements in Hammocks, of which the following is a specification.

My invention relates to hammocks and particularly to that class known as couch hammocks.

The object of my invention is to provide an improved hammock of this kind and also to provide an article of this class which can be used either as a couch or hammock.

15 The invention resides in the novel features of construction and combination of parts set forth in the following description and particularly pointed out and defined in the claims at the close thereof.

20 In the accompanying drawings:—Figure 1 is a front elevation of a hammock constructed in accordance with my invention. Fig. 2 is a section on line 2—2 of Fig. 1. Fig. 3 is a plan view of one end of the frame 25 of my improved hammock. Fig. 4 is an elevation of one of the end shields of the hammock shown in Fig. 1. Fig. 5 is a detail in perspective. Fig. 6 is a section on line 6—6 of Fig. 4. Fig. 7 is a section on 30 line 7—7 of Fig. 4. Fig. 8 is a detail showing a modification.

The frame of my improved hammock 35 comprises two side bars a , a and two end bars a' , a' , fastened together at their ends, the end bars a' being made from angle iron and being provided each with a series of holes in which are hooked the ends of 40 springs that form part of the usual spring mattress b which supports the usual cushion c , indicated by dotted lines in Fig. 1. Pivoted at a^2 to each side bar a , near the ends thereof, are two legs a^3 and the two legs a^3 at each end of the frame are connected by cross bars a^4 and a^5 , the upper cross bar a^4 45 being arranged to engage the side bars a and thereby serve as a stop to limit the outward swing of the pair of legs on their pivots a^2 . That is, when the legs a^3 are in their open or operative positions, as indicated by dotted 50 lines, the cross bars a^4 bear against the under sides of the side bars a with the two pairs of legs spread apart at their lower ends so that when resting on the ground the frame is rigidly and securely supported by the legs 55 and the device can be used as a couch or

settee. When the device is to be used as a hammock the legs a^3 are swung upward into positions alongside the side bars a where they are held by the friction at the joints a^2 .

The wind shield of my hammock 60 comprises three sections as heretofore, but is peculiarly constructed so that it is self supporting and operative either when the device is used as a couch or as a hammock. Heretofore the wind shields of hammocks of 65 this class were held in operative position by the supporting chains or ropes and, moreover, were permanently fastened by screws or otherwise to the frame so that as a practical matter only one side of the hammock 70 and its cushion were subjected to wear which was objectionable. In my hammock the shield sections are separably connected with the frame and the side section can be placed at either side of the hammock or shifted 75 from one side to the other. As herein shown I provide two end sections d , see Fig. 4, each of which comprises a top marginal bar d' of metal and two side marginal bars d^2 of metal, the ends of the top bar d' being 80 fastened by rivets d^3 to the uprights d^2 . These bars d' and d^2 are arranged within pockets provided at the margin of a sheet of canvas d^4 or the like, said pockets being 85 formed by folding the edges of the canvas around the bars and fastening them in those positions by stitches. The upper and lower ends of the upright bars d^2 project beyond the canvas d^4 , said bars being each made at its upper end with a perforation d^5 to receive the hook e of the supporting chain e' , and with a stud d^6 which, as described later, 90 serves to support the adjacent end of the side section of the shield. At their lower ends the upright bars d^2 are formed with 95 perforations d^7 through which extend threaded studs d^8 provided at the ends of said bars a on which studs the bars are held by thumb nuts a^7 . The side section f is 100 made from a sheet of canvas or the like whose top edge is folded upon itself and stitched to form a pocket within which is arranged a marginal bar f' to each end of which is fastened a metal hook or strap f^2 105 through which one of the upright bars d^2 of the adjacent end section extends, said hook or strap f^2 resting on the stud d^6 of said bar in a position immediately below the hook e of the adjacent chain e' . Along the 110 vertical sides of each shield section are pro-

vided eyelets g to receive lacings h by means of which the corners of the shield are fastened together, while the shield f is provided with an additional set of eyelets g near its bottom edge to receive lacings h by means of which it is fastened to one of the side bars a .

The supporting chains herein shown are each provided with hooks e to engage the upright bars d^2 , and with a heart-shaped hanger e^2 near its middle that is adapted to be fastened by another chain or otherwise to the fixture on which the hammock is hung.

When the device is used as a hammock the legs a^3 occupy their inoperative positions and, as will be clear, the whole weight of the frame and of the person seated upon it is borne by the uprights d^2 and the supporting chains so that the canvas parts of the wind shield are not subjected to injurious strains. It will also be clear that the side section f can be placed at either side of the hammock and shifted from one side to the other at will.

When it is desired to provide a settee or couch the legs a^3 are swung down into their operative positions, indicated by dotted lines, and the hooks e disengaged from the uprights d^2 . The device then rests upon the legs and can be used as an ordinary couch or settee, the uprights d^2 of the end shield section d serving to hold the whole shield firmly in its operative position. If desired the device may be provided with two side sections f when used as a couch or bed and with a top section or mosquito netting or the like so that the occupant will be protected from wind and mosquitoes when using it in the open.

In Fig. 8 I have shown a modified form of connection between the lower ends of bars d^2 and the frame. In this case, the lower ends of bar d^2 are formed with hooks d^{10} engaging loops d^{11} on the frame. The hooks d^{10} are normally locked to the loops but by folding the end section down onto the body the hook can be disengaged from the loop and the end section removed.

When the device is set up and used as a hammock or couch the shield d, f , owing to its peculiar construction, is firm and stiff and can be used as a back or side rest. When set up as a settee the wind shield can, if desired, be taken off by removing the thumb nuts a^7 .

My improved hammock is of simple and inexpensive construction.

The operation of setting up and dismantling is simple and quickly performed and its convertibility gives to it a wider range of use than has been possible with hammocks of this class as heretofore constructed.

What I claim is:

1. A convertible couch and hammock, comprising a rigid mattress supporting frame 65 work having legs thereunder mounted for movement to inoperative position out of the way at will, a rigid upstanding frame secured to said frame work having side and end portions mutually interbraced, wind 70 shield members secured to said side and end portions, and means for suspending the device from the top of said upstanding frame when used as a hammock.

2. A convertible couch and hammock, comprising a rigid mattress supporting frame work having legs thereunder pivotally mounted to be swung to operative position or out of the way at will, a rigid upstanding frame secured to said frame work consisting of end and side portions, having provision for mutual interbracing both in and out laterally and endwise, wind shield portions secured thereto, and means for suspending the device from the tops of the end 85 portions of said upstanding frame when used as a hammock.

3. A device of the kind described, comprising a rigid mattress supporting frame work, an upstanding frame secured thereto composed of end and side sections having connections for mutual interbracing in both directions both laterally and endwise, and means for suspending the device from the tops of the end portions of said frame. 90

4. In a hammock of the character described, in combination, a frame; a shield comprising two end sections and a side section, each end section comprising two rigid upright marginal bars, a rigid top marginal 100 bar connected at its ends to said upright bars near the upper ends of the latter and a piece of canvas or the like permanently secured to the top and upright marginal bars, and said side section comprising a rigid 105 top marginal bar provided at its ends with means fastening it to the upper portions of the end sections so as to hold said upper portions bar against movement in either direction longitudinally of said bar, and a 110 piece of canvas or the like secured to said top marginal bar; means separably connecting the lower ends of the upright bars of each end section with the frame with provision for removal without requiring movement of said upright bars relatively, and chains or the like connected with the upper ends of said upright bars.

In testimony whereof I have affixed my signature, in presence of two witnesses.
